UNITED STATES PATENT OFFICE.

ELMYR A. LAUGHLIN, OF CHICAGO, ILLINOIS.

SIDE BEARING.

1,163,020.

Specification of Letters Patent.

Patented Dec. 7, 1915.

Application filed February 17, 1913. Serial No. 748,956.

To all whom it may concern:

Be it known that I, ELMYR A. LAUGHLIN, a citizen of the United States of America, and a resident of Chicago, county of Cook, 5 and State of Illinois, have invented certain new and useful Improvements in Side Bearings, of which the following is a specification.

The main objects of this invention are to 10 provide an improved form of side bearing for railway cars of the type illustrated in my Patent No. 1,000,926, of August 15, 1911, wherein the load is transferred from the roller periphery to the trunnions when the 15 rollers approach either limit of their travel; to provide an improved form of side bearing of this kind which eliminates all followers or roller carriages and springs; to provide an improved construction of the bearing 20 whereby, when the load is transferred from the periphery of the rollers to the trunnions, the car body is caused to be slightly raised during the relative rotary movement of the truck and car, so that the weight of the car 25 has a tendency to urge the truck into its normal position for travel on a straight track; and to provide improved means adapted to facilitate centering of the rollers in the runways at times when the load is relieved therefrom.

An illustrative embodiment of this invention is shown in the accompanying drawings in which:

Figure 1 is a bottom plan view of the side bearing. Fig. 2 is a side elevation partly sectional of the same. Fig. 3 is an end elevation partly sectional.

In the construction shown in the drawings, a bearing member or frame 4 open at 40 the bottom is provided with a roller runway 5 and trunnion guideways 6 at opposite sides of the runway. A single roller 7 is mounted in the runway 5 and is provided with trunnions 8 extending into the guideways 6. The frame 4 is provided with channels 9 extending into the guideways 6 through which the trunnions 8 are adapted 45 to pass when the roller 7 is being inserted into or removed from the runway 5. When 50 the roller 7 is in place blocks 10 are inserted into the channels which form a continuation of the guideways 6 and prevent the displacement of the rollers 7. The blocks 10 are secured on the frame by means of bolts 55 11 which locate the blocks in place by being secured to lugs 12 on the sides of the frame.

A wear-plate 13 is arranged in the frame 4 so as to bear upon the periphery of the roller 7 during the intermediate part of its travel. The upper guide surfaces 14 of the guideways 6 are inclined upwardly and inwardly adjacent to the ends of the runway 5. These upper guide surfaces engage the trunnions 8 when the roller approaches either limit of its movement, and transfer the load from the periphery of the roller 60 to the trunnions. The inclination of the guide surfaces 14 also tends to slightly elevate the frame 4, and the parts carried above, as the roller reaches the extreme limit 65 of its travel, during the time the car is making a curve. As the car passes out of the curve, the inclined surfaces 14 bearing on the trunnions 8 tend to facilitate the centering of the truck with respect to the car. 70 75

The lower inclined guide surfaces 15 are adapted to normally urge the roller toward a central position in the runway 5 at any time when the load is relieved from the roller. The inner faces of the blocks 10 are 80 made concave, as indicated at 16, so as to positively center the roller in the runway 5 when the load is relieved therefrom and prevent it from rolling back and forth and gradually finding its central position. This 85 depression also prevents to a large extent the throwing of the roller to the end of its runway by momentum, when the application of brakes suddenly checks the speed of the car, and at the same time causes a tilting 90 of the trucks on the center bearings and removes the load from the side bearings. A modification of this feature is described and more broadly claimed in my copending application Serial No. 814,921, patented March 95 9, 1915, No. 1,131,252.

The frame 4 is provided with ears 17 having apertures 18 by means of which the bearing is secured to the car body.

The operation of the device will be readily 100 understood from the foregoing description.

Although but one specific embodiment of this invention has been herein shown and described, it will be understood that numerous details of the construction shown may 105 be altered or omitted without departing from the spirit of this invention as defined by the following claims.

I claim:

1. A side bearing, comprising a frame 110 having therein a roller runway, a roller mounted in said runway and adapted to have

a limited range of travel therein, trunnions on said roller, said frame having a bearing surface adapted to engage the periphery of said roller for supporting the load when the roller is in an intermediate part of its travel, said frame also having inclined guide surfaces adapted to engage said trunnions when said roller approaches the limit of its travel so as to transfer the load from the periphery of said roller to said trunnions.

2. A side bearing, comprising a frame having therein a roller runway and guideways at the sides thereof; a roller mounted in said runway and adapted to have a limited range of travel therein, trunnions on said roller, extending into said guideways, said frame having a bearing surface adapted to engage the periphery of said roller for supporting the load when the roller is in an intermediate part of its travel, said frame having the upper and lower surfaces of said guideways at opposite sides of the center diverging inwardly, said upper guide surfaces being adapted to engage said trunnions when said roller approaches either limit of its travel so as to transfer the load from the periphery

of said roller to said trunnions, said lower guide surfaces being adapted to engage said trunnions and cause said roller to center itself in said runway when the load is relieved therefrom.

3. A side bearing, comprising a support having a roller runway formed therein, a roller mounted in said runway and adapted to have a limited range of travel therein, a trunnion on said roller, said frame having a guide surface located to support said trunnion when the load is relieved from said roller, said guide surface being inclined to cause said roller to return by gravity to a substantially central position and having therein a depression serving as a seat for said trunnion when the roller is in such central position, said depression having abrupt shoulders at its ends for confining the roller definitely in such central position.

Signed at Chicago this 13th day of February 1913.

ELMYR A. LAUGHLIN.
